CONTROL KNOB FOR A PATTERN CAM

John P. Enos, Union, N. J., assignor to The Singer Manufacturing Company, Elizabeth, N. J., a corporation of New Jersey

Application October 8, 1954, Serial No. 32,593

Term of patent 14 years

(Cl. D70—2)

Fig. 1.

Fig. 2.

Fig. 3.

Fig. 4.

Fig. 5.

Fig. 1 is a perspective view of the control knob for a pattern cam;

Fig. 2 is a side elevational view thereof;

Fig. 3 is a top plan view;

Fig. 4 is a bottom plan view, and

Fig. 5 represents a cross section taken substantially along line 5—5 of Fig. 3.

What I claim herein is:

The ornamental design for a control knob for a pattern cam, substantially as shown.
